UNITED STATES PATENT OFFICE

135,236

DESIGN FOR A COMBINED BOTTLE, CLOSURE CAP, AND APPLICATOR

James L. Younghusband, Chicago, Ill.

Application March 22, 1940, Serial No. 91,149

Term of patent 14 years

To all whom it may concern:

Be it known that I, James L. Younghusband, a citizen of the Dominion of Canada, residing at 30 West Hubbard Street, Chicago, Illinois, have invented a new, original, and ornamental Design for a Combined Bottle, Closure Cap, and Applicator, of which the following is a specification, reference being had to the accompanying drawing, forming a part thereof.

Fig. 1 is a perspective view of a combined bottle, closure cap, and applicator showing my new design; Fig. 2 shows a top plan view of the bottle with the cap removed and Fig. 3 is a bottom plan view of the cap.

The dominant feature of the design resides in

a bottle of circular vase shaped contour curving from the neck directly outwardly and downwardly for substantially one-quarter of the height of the bottle, where its maximum width is substantially double that of the width of the neck, and continuing with straight lines sloping downwardly and inwardly the remaining three-quarters of the bottle to a rounded bottom substantially one-quarter larger in width than the width of the neck.

I claim:

The ornamental design for a combined bottle, closure cap, and applicator, substantially as shown and described.

JAMES L. YOUNGHUSBAND.
